UNITED STATES PATENT OFFICE.

EDWIN PHELPS AND WALTER J. PHELPS, OF BALTIMORE, MARYLAND.

CAN-SOLDERING MACHINE.

SPECIFICATION forming part of Letters Patent No. 629,918, dated August 1, 1899.

Application filed October 15, 1898. Serial No. 693,644. (No model.)

To all whom it may concern:

Be it known that we, EDWIN PHELPS and WALTER J. PHELPS, citizens of the United States, residing at Baltimore, State of Maryland, have invented a new and useful Can-Soldering Machine, of which the following is a specification.

This invention relates to can-soldering machines of that type in which the can to be soldered is rotated while held in an inclined position with relation to the solder-pot; and it has for its object the construction of a simple and practical machine having every adjustment necessary for handling cans of different sizes.

The invention also contemplates improved means for supporting the different parts of the machine, and especially for "chucking," rotating, and releasing the can to be soldered.

A further object of the invention is to provide a novel construction of framework for supporting the can-soldering devices in duplicate and in convenient positions, so as to enable two workmen to use the machine at the same time, one being engaged in soldering "tops," while the other workman may be engaged in soldering the "bottoms" of the cans, thus greatly facilitating and expediting the handling of the articles.

With these and other objects in view, which will readily appear as the nature of the invention is better understood, the same consists in the novel construction, combination, and arrangement of parts hereinafter more fully described, illustrated, and claimed.

The essential or characteristic features of the can-soldering machine are necessarily susceptible to a variety of modifications without departing from the spirit or scope of the invention; but the preferred embodiment of the invention is shown in the accompanying drawings, in which—

Figure 1 is a perspective view of a double can-soldering machine constructed in accordance with the present invention. Fig. 2 is a side elevation, partly in section, of a portion of the machine, exposing the can handling and soldering devices at one side thereof. Fig. 3 is a vertical transverse sectional view on the line 3-3 of Fig. 2. Fig. 4 is a top plan view of one end portion of the machine, exposing the relative positions of the solder-

pot, the adjustable soldering-iron, and the revoluble supporting-step for the can. Fig. 5 is a detail in perspective of the soldering-iron and its supporting-bracket. Fig. 6 is a detail in perspective of the solder-pot. Fig. 7 is a detail vertical sectional view of the double bearing-bracket on the line 7-7 of Fig. 2. Fig. 8 is a detail in perspective of the revoluble gear-block, the feather-key, and a portion of the longitudinally-movable and revoluble chuck-shaft. Fig. 9 is a similar view of the adjusting-collar for the chuck-shaft. Fig. 10 is a detail in perspective of the flanged chuck-head for the can. Fig. 11 is a similar view of the revoluble supporting-step for the can.

Referring to the accompanying drawings, the numeral 1 designates an elongated arched bed-plate supported near its opposite ends on the oppositely-located upright supporting stands or legs 2, which supporting stands or legs sustain the bed-plate 1 at a sufficient elevation for conveniently manipulating the cans to be soldered. The arched bed-plate 1 is angled in the direction of its length to form a central or intermediate horizontal portion 3, opposite inclined side portions 4, declining from the central portion 3, and the terminal horizontal tables 5 at its opposite extremities and which terminal tables 5 constitute the working-tables at which the operators stand to handle the cans during the operation of the machine.

Each terminal table 5 of the bed-plate 1 is provided therein with a rectangular pot-opening 6, through which projects the upper end of the solder-pot 7. The solder-pot for each table of the machine is rectangular in cross-section and of a downwardly-flaring form, so as to have the shape approximately of a truncated pyramid, and in the present invention the portion of the solder-pot which projects upwardly through the pot-opening 6 is of a less cross-sectional area than the said opening, so as to leave an annular air or cooling space 7 between the walls of the pot and the edges of the opening 6, so that the highly-heated walls of the solder-pot will not communicate heat to the table 5, and thereby heat up the parts attached to the table, so as to seriously interfere with the proper soldering of the can. Each solder-pot 7, which is

arranged within the pot-opening 6 in the position described, is provided at the top with a shallow basin 9 for holding the molten solder, and this basin is formed with an approximately semicircular corrugated bottom portion 10, the corrugations of which bottom portion serve to increase the heating area, and thereby insure a quicker heating of the solder within the basin. Below the corrugated bottom 10 of its solder-holding basin the solder-pot 7 is formed with an elongated heat-chamber 11, which is designed to receive therein a suitable burner 12 for directing the flame therefrom against the corrugated bottom 10 of the said basin, and by reason of providing the pot with an extended heat-chamber 11 below the solder-basin the heat from the burner is confined and concentrated, so that the solder is always maintained in a proper melted condition.

In order to adapt the solder-pot 7 to the various adjustments of the machine for different sizes of cans, it is necessary to support the pot so that the same will be capable of vertical adjustment, and to provide for this the pot 7 is provided on opposite sides and at the lower end thereof with the offstanding perforated lugs 13, which receive therethrough the threaded supporting-bolts 14. The threaded supporting-bolts 14 are rigidly fitted at their upper ends to the table 5 at opposite sides of the pot-opening 6 therein and receive thereon the fastening-nuts 15. Each bolt 14 has a pair of nuts 15, arranged, respectively, above and below the lugs of the pot, so that by a proper manipulation of the nuts the solder-pot can be readily adjusted in a vertical direction to correspond with the other adjustments of the machine and then be fastened or secured in its adjusted position, as may be plainly seen from Fig. 3 of the drawings.

In connection with each solder-pot supported by each table of the machine there is employed a soldering-iron 16. The soldering-iron 16 essentially consists of a flat bar provided between its ends with a semicircular seat portion 17 to embrace the portion of the can being soldered, and the straight terminals of the iron 16 are provided therein with longitudinally-disposed slots 18, crossing similarly-disposed slots 19, formed in the upper ends of the inclined arms 20 of the supporting-brackets 21 for the iron. The supporting-brackets 21 for each soldering-iron 16 are arranged, respectively, at opposite sides of the pot-opening 6 in the table 5 and are provided in their horizontal portions with longitudinally-disposed slots 22, which receive the fastening-bolts 23, that engage threaded openings formed in the table 5, thereby providing an adjustable connection between said brackets and table, whereby the former may be adjusted with relation to the proper position of the soldering-iron within the top basin of the solder-pot.

The oppositely-located supporting-brackets 21 for each soldering-iron are substantially

L-shaped; but the arms 20 thereof are disposed obliquely to their horizontal portions, so that said arms will stand in an inclined position, and thereby dispose the soldering-iron obliquely and at right angles to the axis of rotation of the can to be soldered, as plainly shown in Figs. 2 and 5 of the drawings. The slotted terminals of the soldering-iron 6 are adjustably connected to the slotted portions of the inclined arms 20 by means of the clamping-bolts 24, which connection enables the soldering-iron to be adjusted longitudinally and vertically to secure a proper centering thereof with respect to the can and also to adjust the same so as to have the proper "dip" in the solder-bath.

At one side of the pot-opening 6 in each working-table 5 of the machine such table has fastened thereon a fixed step-bearing 25, having a tubular portion disposed at an inclination and receiving in the upper open end thereof the stem or shaft portion 26 of the revoluble step-block 27, forming the lower rest 90 or support for the can to be soldered. The stem or shaft portion 26 of the supporting-step 27 for the can loosely turns in the inclined step-bearing 25 and is longitudinally adjusted therein through the medium of an adjusting set-screw 28, mounted in the threaded opening in the closed end of the bearing 25 and impinging against the inner lower end of the stem or shaft 26. By reason of the employment of the set-screw 28 it will be observed that the same gives a double adjustment to the step-block 27—namely, in a longitudinal and also in a vertical direction—which adjustments correspond to the adjustments of the soldering-iron 16, so that the step-block 105 27 can always be properly centered with respect to the circular seat portion 17 of the soldering-iron, it being observed that said seat portion of the soldering-iron and the step-block should be concentric to insure the proper support and soldering of the can.

Cooperating with the revoluble supporting-step 27 on each table of the machine is a longitudinally-movable revoluble chuck-shaft 29. Each revoluble chuck-shaft 29 is arranged above and parallel with an inclined side portion 4 of the bed-plate 1 and carries at its lower end, above the table 5, a flanged chuck-head 30, designed to clamp over the end of the can C opposite the end resting on the step-block 27, and said flanged chuck-head is provided with a collar portion detachably held onto the lower end of the chuck-shaft by means of a fastening-screw 31. The detachable connection between the chuck-head 30 and the lower end of each chuck-shaft 29 permits different sizes of chuck-heads to be fitted on the chuck-shaft, according to the size of the cans to be soldered.

Each of the inclined chuck-shafts 29, arranged, respectively, over the opposite inclined portions 4 of the bed-plate, is supported for a sliding and rotary movement in the oppositely-arranged bearing-brackets 32 and

33, respectively. Both of said brackets are stationary; but the bracket 32 is fastened to the inclined portion 4 of the bed-plate and the bracket 33 fastened to the central horizontal portion 3 of the bed-plate, it of course being understood that these brackets are arranged in duplicate at both sides of the vertical center of the machine. The inner fixed bearing-bracket 33 for each revoluble chuck-shaft is formed in three sections assembled together to provide a double bearing, said sections being designated, respectively, by the numbers 34, 35, and 36.

The lower section 34 of each bearing-bracket 15 33 has a flange-and-bolt connection 37 with the intermediate section 35, which has a similar flange-and-bolt connection 38 with the upper or cap section 36, and between the abutting sections 34 and 35 is formed a horizontal bearing 39 for the horizontal driving-shaft 40, arranged horizontally above the central portion 3 of the bed-plate and carrying the loose and fast pulleys 41 and 42, respectively, for receiving the driving-belt 43. The opposite 25 ends of the driving-shaft 40 are journaled in the bearings 39 of the oppositely-located brackets 33, and each of said brackets 33 has formed between the intermediate and upper sections 35 and 36 thereof an inclined bearing 44, in which is revolvably mounted an annularly-grooved gear-block 45, provided at one end with a bevel-gear 46, meshing with a corresponding gear 47 on the contiguous 30 terminal of the driving-shaft 40.

35 Each revoluble gear-block 45 is provided within the bore thereof with a longitudinal key seat or groove 48, adapted to receive therein a feather-key 49, having retaining-shoulders 50 at its ends engaging the ends of 40 the gear-block to obviate relative displacement. The said feather-key 49 loosely registers in a longitudinal feather-groove 51, formed in the inclined chuck-shaft 29 and extending, in the practical construction of the machine, 45 substantially one-half the length of such shaft. Each chuck-shaft 29 is thus slidably mounted in the revoluble gear-block 45, mounted in the inner bearing-bracket 33 for such shaft, while at the same time the feather 50 connection between these parts provides for a constant rotation of the shaft 29 entirely independent of its sliding movement, and each chuck-shaft 29 is normally forced in a longitudinal direction toward the revoluble 55 step 27 through the medium of a pressure-spring 52.

The revoluble pressure-spring 52 for each chuck-shaft 29 is arranged on such shaft and interposed between the gear end of the block 60 45 and the adjusting-collar 53, adjustably fastened on the shaft by means of the screw 54 at one side of the bearing-bracket 32. The adjusting-collar 53 is provided with an annular groove 55, receiving the forked end 56 of 65 a bell-crank adjusting-lever 57, fulcrumed intermediate its ends, as at 58, in the bed-plate 1 and having attached to its arm below

the bed-plate an operating-rod 59, leading to a treadle 60, hinged to the floor supporting the machine. Normally the spring 52 forces 70 the chuck-shaft 29 in a downward direction, and thereby causes the chuck-head 30, carried thereby, to clamp over one end of the can to be soldered; and the adjusting-collar 53 should be so adjusted that when the chuck-head 75 engages the can-body said collar will not contact with the bearing-bracket 32 and will thereby allow the full pressure of the spring 52 to be exerted against the can-body, so that the latter will be held tightly chucked 80 between the oppositely-located chuck-head 30 and supporting-step 27. The rotation of the chuck-shaft 29 causes the can-body to rotate within the circle of the soldering-iron 16, and when the soldering is effected the operator simply depresses the treadle 60, which, through the medium of the connections described, slides the shaft in a line backward and upward through the gear-block 45 and releases the soldered can, which can then be 85 thrown aside and replaced by an unsoldered can, which operation is continually repeated 90 during the working of the machine.

The relative adjustments of the revoluble supporting-step, of the soldering-iron, and 95 of the solder-pot to adapt the machine for different sizes of cans have already been referred to, and in order to adjust each chuck-shaft 29 for the same purpose it is simply necessary to loosen the adjusting-collar 53 and 100 slide the shaft 29 longitudinally through its bearings to the proper position, said chuck-shaft being capable of adjustment for use in connection with any length of can ranging from one inch up to nine inches, thereby giving 105 the machine a wide range of adjustment, so that the same can be used for soldering all ordinary sizes of cans.

From the foregoing it is thought that the construction, operation, and many advantages 110 of the herein-described can-soldering machine will be readily understood by those skilled in the art without further description, and it will further be understood that changes in the form, proportion, and the minor details 115 of construction may be resorted to without departing from the principle or sacrificing any of the advantages of this invention.

Having thus described the invention, what is claimed as new, and desired to be secured 120 by Letters Patent, is—

1. In a can-soldering machine, a bed-plate having a pot-opening therein, a vertically-adjustable solder-pot suspended from the under side of the bed-plate and projecting upwardly 125 through and above the plane of the pot-opening, said pot being of less cross-sectional area than the pot-opening, a soldering-iron supported on the top of the bed-plate for vertical adjustment independently of the pot, said 130 soldering-iron projecting into the pot, and a revoluble can-support having an adjustment corresponding to the adjustment of the pot and the iron, substantially as set forth.

2. In a can-soldering machine, the bed-plate having a pot-opening therein, a solder-pot lying within said opening out of contact with all of its edges and projecting above and below the same, said solder-pot being provided on opposite sides at the lower end thereof beneath the bed-plate with offstanding perforated lugs, stationary supporting-bolts depending from the bed-plate and extending through the perforated lugs of the pot, fastening-nuts engaging the bolts respectively at opposite sides of said lugs, and a can-handling device, substantially as set forth. 70
3. In a can-soldering machine, the bed-plate, a solder-pot adjustably supported by the bed-plate, a soldering-iron also adjustably supported by the bed-plate independently of the pot, and projecting into the latter, and a revolute can-support arranged on the bed-plate and adjustable relatively to the adjustable pot and soldering-iron, substantially as set forth. 80
4. In a can-soldering machine, the bed-plate, a vertically-adjustable solder-pot, an arched soldering-iron supported for vertical adjustment independent of the pot and projecting therein, and a revolute can-support arranged on the bed-plate and adjustable relatively to the adjustable pot and soldering-iron, substantially as set forth. 90
5. In a can-soldering machine, the supporting-bed, a vertically-adjustable solder-pot, a soldering-iron supported for vertical adjustment independent of the pot, and a revolute can-support having an adjustment corresponding to the adjustment of the pot and the iron, substantially as set forth. 95
6. In a can-soldering machine, the supporting-bed, a vertically-adjustable solder-pot, a soldering-iron supported on the bed and adjustable transversely of the pot and also in a vertical direction, and a revolute can-support adjustable to different lengths of cans and also having an adjustment corresponding to the vertical adjustment of the pot and the iron, substantially as set forth. 105
7. In a can-soldering machine, the supporting-bed, a solder-pot, an obliquely-arranged soldering-iron having a semicircular seat portion dipping in the pot, and a revolute can-support arranged at an inclination and concentric with the seat portion of the soldering-iron, substantially as set forth. 115
8. In a can-soldering machine, the supporting-bed, a solder-pot, an obliquely-arranged soldering-iron having a semicircular seat portion dipping in the pot, means for adjusting the soldering-iron transversely of the pot and also vertically, and a revolute can-support arranged at an inclination concentric with the seat portion of the iron and adjustable to different lengths of cans, substantially as set forth. 120
9. In a can-soldering machine, the combination with the soldering-pot and the inclined revolute can-support, of supporting-brackets arranged at opposite sides of the pot and having inclined arms, and a vertically and longitudinally adjustable soldering-iron having adjustable connection with said inclined arms and provided with a semicircular seat portion dipping in the pot, substantially as set forth. 75
10. In a can-soldering machine, a supporting-bed, a solder-pot, a solder-iron adjustable transversely of the pot and also in a vertical direction, and a can-support adjustable to different lengths of cans and also having an adjustment corresponding to the vertical adjustment of the iron, substantially as set forth. 80
11. In a can-soldering machine, the combination with the bed, the can-support, and the solder-pot; of an adjustable soldering-iron support fitted to the bed, and a soldering-iron having adjustable connection with its adjustable support, whereby said iron may have an independent adjustment transversely of the pot, and also in a vertical direction, substantially as set forth. 85
12. In a can-soldering machine, the bed-plate having a table supporting the solder-pot, an inclined supporting-step mounted on the table, oppositely-arranged bearing-brackets mounted on the bed-plate, the inner of said brackets having an inclined bearing and also a lower horizontal bearing, a drive-shaft mounted in said lower horizontal bearing and carrying a gear-wheel, a revolute gear-block mounted in said inclined bearing and having a gear meshing with the gear of the drive-shaft, and a longitudinally-movable and revolute inclined chuck-shaft carrying a chuck-head and having a sliding feather connection with said gear-block substantially as set forth. 95
13. In a can-soldering machine, the bed-plate having a table supporting the solder-pot, an inclined supporting-step mounted on the table, oppositely-arranged bearing-brackets mounted on the bed-plate, the inner of said brackets having an inclined bearing, and a lower horizontal bearing, a driving-shaft mounted in said lower horizontal bearing and carrying a gear-wheel, a revolute gear-block mounted in said inclined bearing and having a gear meshing with the gear of the driving-shaft, a revolute inclined chuck-shaft carrying a chuck-head and having a sliding feather connection with said gear-block, said chuck-shaft also turning and sliding in the outer of said bearing-brackets, an adjusting-collar adjustably mounted on the chuck-shaft, a spring interposed between the gear-block and said adjusting-collar, and a treadle having lever connections with said adjusting-collar, substantially as set forth. 105
14. In a can-soldering machine, the bed-plate having a central horizontal portion, opposite inclined side portions and terminal horizontal tables at its extremity, solder-pots supported by said terminal tables, supporting-steps mounted at an inclination on the terminal tables, opposite pairs of bearing-brackets mounted respectively on the in- 130

clined and central horizontal portions of the bed-plate, said bearing-brackets on the central horizontal portion of the bed-plate having separate upper and lower bearings, the upper of which bearings are disposed at an angle, revoluble and longitudinally-movable and adjustable chuck-shafts arranged above and parallel with the inclined portions of the bed-plate, and a horizontal driving-shaft arranged parallel with the central portion of the bed-plate and journaled in the lower bearings

of the bracket mounted thereon, said driving-shaft having gear connections with the chuck-shafts, substantially as set forth.

In testimony that we claim the foregoing as our own we have hereto affixed our signatures in the presence of two witnesses.

EDWIN PHELPS.
WALTER J. PHELPS.
